UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,604, dated August 28, 1894.

Application filed August 3, 1894. Serial No. 518,376. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of Greek palmette-shaped figures or ornaments arranged at uniform distances apart, as represented in the accompanying drawing. The said figures or ornaments are filled with light irregular transverse lines forming a stitch effect as shown. The border or upper portion of the design is formed of said Greek palmette-

shaped ornaments with a series of filigree scrolls connecting said ornaments as shown in the drawing.

What I claim is—

1. The design for wall paper herein shown and described.
2. In the design for wall paper, the border herein shown and described.

Witness my hand this 31st day of July, 1894.

CHARLES BOOZE.
